UNITED STATES PATENT OFFICE.

CARL STILL, OF RECKLINGHAUSEN, GERMANY.

HORIZONTAL COKE-OVEN.

1,098,188.

Specification of Letters Patent. Patented May 26, 1914.

Application filed January 23, 1912. Serial No. 772,928.

To all whom it may concern:

Be it known that I, CARL STILL, a subject of the German Emperor, residing at Recklinghausen, Westphalia, in the German Empire, have invented certain new and useful Improvements in Horizontal Coke-Ovens, of which the following is a specification.

This invention relates to horizontal coke ovens having vertical heating flues to which the heating gas is supplied through channels formed within the underlying refractory masonry, and it is the object of the invention to provide means whereby the disadvantages and disturbances commonly connected with such a system for supplying gas to the heating flues are avoided and a continuous and uniform distribution of the gas to all parts where combustion occurs is guaranteed.

It is common practice to conduct the heating gases to the vertical heating flues of such horizontal coke ovens through nozzles arranged one at the foot of each heating flue and having orifices of small cross section; this cross section has to be carefully determined in order that the distribution of the gas and consequently the heating of all the flues may be uniform. Owing to the high temperature prevailing in the whole masonry at the bottom of the heating flues the gas passing through the nozzle becomes heated to such a temperature that it is partially decomposed and carbon is liable to be deposited within the nozzle, thus choking it and preventing the passage of the correct amount of gas for the proper heating of the flue. Another cause of such obstruction is the peeling off of particles of the material of which the heating flue is constructed, which particles either cover or enter the orifices of the nozzles and choke them. This difficulty arises from the narrow cross section of the orifice which, however, must be maintained for the reason aforesaid.

The present invention minimizes the liability of disturbances due to the small cross section of the orifices of the nozzles by providing each heating flue with two nozzles, one vertically above the other, the lower being the nozzle for the distribution of the gas and the upper a combustion nozzle adapted to protect the lower nozzle. The lower distributing nozzle has the necessary narrow cross section aforesaid, but it is situated at such a distance below the upper combustion nozzle that its temperature is com-

paratively low and decomposition of the heating gases passing through it is not liable to occur. The upper nozzle is situated at the bottom of the heating flue but has an orifice of greater cross sectional area than that of the orifice of the lower nozzle so that the correct volume of heating gases can pass even should the nozzle become partially obstructed from either of the causes aforesaid.

In the accompanying drawings, Figure 1 is a longitudinal section through the heating wall of a coke oven provided with duplicate nozzles according to the invention. Fig. 2 is an enlarged portion of the said section.

The lower distributing nozzles *a* have passages of the correct cross section for determining the proper distribution of the heating gases in the heating flues, while the upper nozzles *b* have passages of larger cross sectional area and are situated one at the bottom of each heating flue which is the customary position. As will be seen the lower nozzle is at a considerable distance below the upper one. The arrow at the bottom of Fig. 2 indicates the passage of the gas from the distributing channel through the nozzle *a*. The arrows shown in the upper part of Fig. 2 indicate the passage of air for burning the heating gas in the flue.

Having thus described my invention and the best means I know of carrying the same into practical effect, I claim:

1. In a horizontal coke oven, the combination comprising vertical heating flues, channels formed completely within and by the underlying masonry and adapted to supply heating gas to the said flues, a gas nozzle of fixed orifice at the lower part of each flue, passages for admission of air for combustion into each flue above this nozzle, a second gas nozzle also of fixed orifice below the first gas nozzle, the orifice of the said second gas nozzle being of smaller cross section than the orifice of the first named gas nozzle.

2. In a horizontal coke oven, the combination comprising vertical heating flues, channels formed completely within and by the underlying masonry and adapted to supply heating gas to the said flues, a gas nozzle of fixed orifice at the lower part of each flue, passages for admission of air for combustion into each flue above this nozzle, a second gas nozzle also of fixed orifice below the first gas nozzle at such a distance therefrom that

it is not strongly heated, the second gas nozzle having an orifice of cross section adapted to pass the volume of gas required for the flue, and the first named gas nozzle having 5 an orifice of cross section greater than that of the orifice of the said second gas nozzle.

3. In a horizontal coke oven, the combination comprising vertical heating flues, channels formed completely within and by the 10 underlying masonry and adapted to supply heating gas to the said flues, a gas nozzle of fixed orifice at the lower part of each flue, passages for admission of air for combustion situated in the oven wall between adjacent 15 flues, outlets branched from the said air passages for delivering air for combustion

into each flue above the said nozzle, a second gas nozzle also of fixed orifice below the first gas nozzle at such a distance therefrom that it is not strongly heated, the said second 20 gas nozzle having an orifice of cross section adapted to pass the volume of gas required for the flue, and the first named gas nozzle having an orifice of cross section greater than that of the orifice of the said second 25 gas nozzle.

In testimony whereof I have affixed my signature in presence of two witnesses.

CARL STILL.
